[57] CLAIM

The ornamental design for a combined bottle and cap, as shown and described.

DESCRIPTION

FIG. 1 is a perspective view of a combined bottle and cap showing our new design;

FIG. 2 is a front elevation view thereof, the rear being the same;

FIG. 3 is a top plan view thereof;

FIG. 4 being a bottom plan view thereof;

FIG. 5 is a perspective view of a bottle and cap showing a second embodiment of our new design;

FIG. 6 is a front elevation view thereof;

FIG. 7 is a rear elevation view thereof;

FIG. 8 is a top plan view thereof; and,

FIG. 9 is a bottom plan view thereof.
